[57] CLAIM

The ornamental design for a camping provisions kit, as shown and described.

DESCRIPTION

FIG. 1 is a perspective view of a camping provisions kit showing my new design with the lid in an open position. FIG. 2 is a top plan view thereof with the lid closed, the bottom surface being plain and unornamented.

FIG. 3 is a rear elevational view.

FIG. 4 is a front elevational view.

FIG. 5 is a right side elevational view.
